Primary Examiner — Mehri F Bajoul

(57) **CLAIM**

The ornamental design for a button attachment cover for game pads, as shown and described.

DESCRIPTION

FIG. 1 is a front, bottom and right perspective view of a button attachment cover for game pads showing my new design;

FIG. 2 is a rear, top and left perspective view thereof;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof;

FIG. 9 is a top and front perspective view of the button attachment cover for game pads in its environment of use; and,

FIG. 10 is another view of the button attachment cover for game pads in its environment of use.

The honeycomb-shaped broken lines on the button attachment cover for game pads, in FIGS. 1, 3, 5, and 8-10 depict portions that form no part of the claim.

1 Claim, 10 Drawing Sheets
